(57) **CLAIM**

I claim the ornamental design for the two-tier turntable, as shown and described.

DESCRIPTION

FIG. 1 is a top perspective view of a two-tier turntable, showing my new design.

FIG. 2 is a front view of the two-tier turntable.

FIG. 3 is a rear view of the two-tier turntable.

FIG. 4 is a right side view of the two-tier turntable.

FIG. 5 is a left side view of the two-tier turntable.

FIG. 6 is a top view of the two-tier turntable; and,

FIG. 7 is a bottom view of the two-tier turntable.

The broken lines depict portions of the article that form no part of the claimed design.
